(57) **CLAIM**

The ornamental design for a blind hole mount, as shown and described.

DESCRIPTION

FIG. 1 is a perspective view of a first embodiment of the blind hole mount;

FIG. 2 is a front elevation view, the rear elevation view being identical;

FIG. 3 is a right side elevation view, the left side elevation view being identical;

FIG. 4 is a top plan view thereof;

FIG. 5 is a bottom plan view thereof;

FIG. 6 is a perspective view of a second embodiment of the blind hole mount;

FIG. 7 is a front elevation view, the rear elevation view being identical;

FIG. 8 is a right side elevation view, the left side elevation view being identical;

FIG. 9 is a top plan view thereof;

FIG. 10 is a bottom plan view thereof;

FIG. 11 is a perspective view of a third embodiment of the blind hole mount;

FIG. 12 is a front elevation view, the rear elevation view being identical;

FIG. 13 is a right side elevation view, the left side elevation view being identical;

FIG. 14 is a top plan view thereof;

FIG. 15 is a bottom plan view thereof;

FIG. 16 is a perspective view of a fourth embodiment of the blind hole mount;

FIG. 17 is a front elevation view, the rear elevation view being identical;

FIG. 18 is a right side elevation view, the left side elevation view being identical;

FIG. 19 is a top plan view thereof; and,

FIG. 20 is a bottom plan view thereof.
